INVENTOR

Christian Aalborg.
BY
Wesley G. Barr
ATTORNEY

UNITED STATES PATENT OFFICE.

CHRISTIAN AALBORG, OF PITTSBURGH, PENNSYLVANIA, ASSIGNOR TO WESTINGHOUSE ELECTRIC & MANUFACTURING COMPANY, A CORPORATION OF PENNSYLVANIA.

SNAP SWITCH.

Application filed August 17, 1920. Serial No. 404,126.

To all whom it may concern:

Be it known that I, CHRISTIAN AALBORG, a citizen of the United States, and a resident of Pittsburgh, in the county of Allegheny and State of Pennsylvania, have invented 5 a new and useful Improvement in Snap Switches, of which the following is a specification.

My invention relates to electric snap switches, and it has for its object the provision of a switch which shall be simple in construction and comprise a small number or parts, and in which simplicity and cheapness of construction are effected without any 10 loss in efficiency or durability.

Referring to the drawings—

Fig. 1 is a plan view of the switch.

Fig. 2 is an end elevation, and

Fig. 3 is a side view, with a portion of the 20 frame removed to more clearly show the working parts.

Referring particularly to Fig. 3, I provide a base 4, made of non-conducting material, on which are mounted the usual posts 25 7, contacts 8, and a frame 9.

Pivoted on the posts 7 are a pair of switch blades 10 to engage the contacts 8, when in closed position. Connecting the blades 10, is a cross head 11, made of a material which 30 is non-conducting; and fastened to the cross head, intermediate its ends, is a bracket 12 which has an extension, at its lower end, to limit the downward movement of the blades, and, at its upper end, is connected to the 35 outer end of a coil spring 13.

The frame 9 is made of one piece, of substantially U-shape, as shown more clearly in Fig. 2. Pivoted in the frame, at 14, is a handle 15, having an arm 16 which is connected to the inner end of the coil spring 13. The inner end of the handle 15 is provided with shoulders 18 and 19 with which a pin 17 coacts to limit the movement of the handle, in either direction. The arm 40 45 16 may either be made integral with the handle 15 or be secured thereto in any desired manner.

The operation of the switch is as follows:

With the switch in its "on", or closed, 50 position, as shown in the drawing, the spring 13, being under tension, exerts an inward pull which holds the blades in the position occupied. If, now, the handle be moved to "off" position, its rotative movement on the

pivot 14 will swing the arm 16, and the end 55 of the spring carried thereby, outwardly and upwardly, thus increasing the tension on the spring and causing it to exert an upward pull on the blades, whereby they will snap to the position shown in dotted lines in Fig. 60 3. When the handle is moved to its "on" position, the action just described is reversed, and the blades are again brought into engagement with the contacts 8.

I claim as my invention:—

1. In a snap switch, a base, a frame, a movable contact member pivotally mounted on the base, a bracket secured to the movable contact member and provided with an outwardly extending portion, a handle pivotally supported in the frame and provided with an arm extending inwardly past the said outer portion of the bracket, and a spring interposed between the said arm and the outer portion of the bracket and adapted to 75 maintain the bracket under tension.

2. A snap switch, comprising, in combination, a frame, a pair of blades pivotally mounted at one end, their other ends cooperating with a pair of contacts, an insulated cross bar connecting the two blades intermediate their ends, a bracket mounted on the cross bar to serve as a stop member for limiting the downward movement of the blades and also serving as a spring support, an operating handle pivoted in the frame, a stop member on the frame, for limiting the movement of the handle, in either direction, an arm secured to the handle and movable therewith, and a coil spring 80 having one end connected to the said arm and its other end connected to the said bracket.

3. In a snap switch, a base, a frame, a movable contact member pivotally mounted 85 on the base, a bracket secured to the movable contact member and provided with an outwardly extending portion, a handle pivotally supported in the frame and provided with an arm extending inwardly past the said outer portion of the bracket, a spring interposed between the said arm and the outer portion of the bracket and adapted to maintain the bracket under tension, and a stop member on the frame for limiting the movement of the handle.

4. In a snap switch, a base, a pair of movable contact members pivotally mounted

on the base, a frame secured to the base between the movable contact members, a bracket secured to the movable contact members and provided with an outwardly extending portion, a handle pivotally supported in the frame and provided with an arm extending inwardly past the said outer portion of the bracket, and a spring interposed between the said arm and the outer portion of the bracket and adapted to maintain the bracket under tension.

5. In a snap switch, a base, a frame mounted on the base, a switch blade having one end pivotally supported on the base, a switch-blade contact mounted in position to be engaged by the free end of the blade, a bracket mounted on the switch blade near the free end thereof, a coil spring normally

under tension and having one end connected to the bracket, an operating handle pivoted in the frame, an arm secured to the handle and movable therewith, and a connection between the other end of said coil spring and the handle whereby, when the handle is moved to open position, the angle of pull exerted by the spring is changed to cause the blade to move out of engagement with the contact and, when the handle is moved to closed position, the direction of pull is changed to move the blade again into engagement with the contact.
